UNITED STATES PATENT OFFICE.

VINCENT BENDIX, OF CHICAGO, ILLINOIS.

ENGINE STARTER.

Application filed October 19, 1922. Serial No. 595,561.

To all whom it may concern:

Be it known that I, VINCENT BENDIX, a citizen of the United States, residing at Chicago, in the county of Cook and State of Illinois, have invented certain new and useful Improvements in Engine Starters, of which the following is a specification.

My invention relates to engine starters, and more particularly to that part thereof known as the drive or transmission. In the present instance such invention is embodied in a drive of the Bendix type exemplified by a screw shaft which is rotated by an electric motor and on which is screw-threaded a driving member, such as a pinion adapted to engage the engine member such as the fly-wheel of an internal combustion engine. The object of my invention is to provide means for relieving the drive against any possible effect of back-fire which causes a backward rotation of the fly-wheel and of the drive. In the present instance, the driving member is made in two parts, one a pinion proper and the other a control member or nut, and in carrying out my invention, I provide an additional member intermediate the fly-wheel and the nut which causes a backing off of the nut in case of backward rotation of the fly-wheel, thereby relieving the drive and motor of any strain.

In the drawings, Figure 1 is an elevation partly in section illustrating a starter system embodying my invention; Fig. 2 a similar view illustrating a portion of the part shown in Fig. 1 but showing the driving member in operating position; Fig. 3 an elevation of one face of the control member or nut; Fig. 4 a section on the line 4-4 of Fig. 3; Fig. 5 an elevation of the other side or face of such control member; and Fig. 6 a plan view of a portion of the brackets.

For the purpose of a clear and definite description of my invention, I have shown the same embodied in a particular form and construction of drive or transmission, but it will be understood that in so far as my invention in its broader aspect is concerned other types and constructions of drive may be employed.

Referring to the particular construction shown in the drawings, an electric motor 1 has an extended armature shaft 2 on which the drive is mounted and by which it is operated. The drive comprises a driving head 3 secured to the shaft 2 by the bolt 4, a hollow screw shaft 5 loosely mounted upon the rotatable driving shaft 2 and provided at its end with a stop nut 6, a driving member which here comprises a pinion 7 and a control member or nut 8, and a drive spring 9 operatively connecting the driving head 3 and the driving head 10 forming a part of the screw shaft, such spring being secured at its opposite ends to the bolt 4 and to the bolt 11, respectively. The drive also includes, in the present instance, a light coil spring 12 in front of the stop nut 6 and pressing against a longitudinally slid able sleeve 13 whose inner reduced end enters within the smooth bore of the pinion. This spring tends to hold the pinion in disengaged position but yields when the drive operates, that is, when the pinion 7 is caused to move outwardly into mesh with the engine member (which is here the fly-wheel 14) by reason of the longitudinal movement of the nut 8. The engaged position of the driving member and fly-wheel is illustrated in Fig. 2.

For the purposes of my invention, I apply to such drive a member located intermediate the fly-wheel and the nut and adapted to cooperate with both of them in case of backward rotation of the fly-wheel such as caused by a back-fire which cannot be held or restrained by the drive and its motor. This intermediate member comprises a roller 15 rotatable on an axis at right angles to the axis of the screw shaft and to the axis of the fly-wheel. It is mounted in a suitable manner in perpendicular position with respect to the screw shaft axis. In the present instance, it is provided with a stem 16 having a limited movement (which is yielding by virtue of the spring 17) in a bracket 18. This bracket is pivoted at 19 to a stationary bracket 20 secured in a suitable manner to the motor frame as by means of the bolts 21. The downward movement of the roller is limited by means of the col-

lar 22 screwed to the end of the stem 16 and the upward movement of such roller is stopped by the contact thereof with the bracket 18 itself. The movable bracket 18 is held to the normal position shown in Fig. 1 against the shoulder 23 of the stationary bracket in a yielding manner as by means of the coil spring 24. In this normal position, the roller is held slightly away from the face of the fly-wheel so that there is clearance between them as shown in Fig. 1. The roller 15 is provided with a cone face 25 which is adapted to cooperate with a truncated cone periphery 26 of the control member or nut 8. The intermediate member or roller is normally free from all of the parts, except of course the hinged bracket in which it is mounted, and is held away from the face of the fly-wheel by the tension spring 24. When the normal meshing operation of the driving member occurs, the control member or nut contacts the intermediate member or roller and the two cone shaped surfaces coming into contact causes a swinging of the roller against the face of the fly-wheel. This lifts the roller upwardly against the compression spring 17 so that in the cranking operation the roller is yieldingly held in frictional contact with the fly-wheel and with the cone surface or periphery of the nut but such roller performs no function during such normal cranking operation. In case of backward rotation of the fly-wheel such as may be caused by back-fire, the roller is rotated through its frictional contact with the fly-wheel in such direction as to cause the nut to be rotated at a speed greater than it is being driven by the screw shaft, with the result that the nut will be backed off and carried out of contact with the free pinion 7, so that no load will be transmitted to the drive or the connected parts through the backward rotation of the fly-wheel. In the case of what is known as a meeting back-fire, that is when electrical contact is made and current supplied to the motor when the fly-wheel is in backward rotation and with the pinion in demeshed position, the nut will contact the roller and cause it, in turn, to contact the backwardly rotating fly-wheel face before the pinion has been clamped between the control nut and the stop nut. As a result and in accordance with the mode of operation above described, the control nut will be screwed away or backed off along the screw shaft through the action of the roller.

I claim:

1. In an engine starter drive, the combination, with a member of the engine to be started, of a rotatable shaft, a driving member mounted thereon for enforced longitudinal movement thereon by the rotation of the shaft and adapted to engage the engine member, and means for relieving such

driving member from such enforced longitudinal movement when the engine member rotates backwardly.

2. In an engine starter drive, the combination, with a member of the engine to be started, of a rotatable shaft, a driving member mounted thereon for enforced longitudinal movement thereon by the rotation of the shaft and adapted to engage the engine member, and means for relieving such driving member from such enforced longitudinal movement when the engine member rotates backwardly, such means comprising a member located between the engine member and the driving member, and normally inoperative but cooperating therewith at the time of such backward rotation of the engine member.

3. In an engine starter drive, the combination, with a member of the engine to be started, of a rotatable shaft, a driving member mounted thereon for enforced longitudinal movement thereon by the rotation of the shaft and adapted to engage the engine member, and means for relieving such driving member from such enforced longitudinal movement when the engine member rotates backwardly, such means comprising a roller having one face to cooperate with the engine member and another face to cooperate with the driving member.

4. In an engine starter drive, the combination, with a member of the engine to be started, of a rotatable shaft, a driving member mounted thereon for enforced longitudinal movement thereon by the rotation of the shaft and adapted to engage the engine member, and means for relieving such driving member from such enforced longitudinal movement when the engine member rotates backwardly, such means comprising a roller having one face to cooperate with the engine member and another face to cooperate with the driving member, said roller being loosely mounted for free rotation and for limited longitudinal movement.

5. In an engine starter drive, the combination, with a member of the engine to be started, of a rotatable shaft, a driving member mounted thereon for enforced longitudinal movement thereon by the rotation of the shaft and adapted to engage the engine member, and means for relieving such driving member from such enforced longitudinal movement when the engine member rotates backwardly, such means comprising a roller having one face to cooperate with the engine member and another face to cooperate with the driving member, and a swinging bracket in which such roller is mounted to rotate.

6. In an engine starter drive, the combination, with a member of the engine to be started, of a rotatable shaft, a driving member mounted thereon for enforced lon-

- 5 gitudinal movement thereon by the rotation of the shaft and adapted to engage the engine member, and means for relieving such driving member from such enforced longitudinal movement when the engine member rotates backwardly, such means comprising a roller having one face to cooperate with the engine member and another face to cooperate with the driving member, a swing-
10 ing bracket in which such roller is mounted for rotary and for longitudinal movement, and means for yieldingly holding the roller toward the driving member.

15 7. In an engine starter drive, the combination, with a member of the engine to be started, of a rotatable shaft, a driving member mounted thereon for enforced longitudinal movement thereon by the rotation of the shaft and adapted to engage the engine
20 member, and means for relieving such driving member from such enforced longitudinal movement when the engine member rotates backwardly, such means comprising a roller having one face to cooperate with the engine member and another face to cooperate with the driving member, a stationary bracket, and a second bracket pivoted thereto, such roller being mounted for rotation in said second bracket.

25 8. In an engine starter drive, the combination, with a member of the engine to be started, of a rotatable shaft, a driving member mounted thereon for enforced longitudinal movement thereon by the rotation of the
30 shaft and adapted to engage the engine member, and means for relieving such driving member from such enforced longitudinal movement when the engine member rotates backwardly, such means comprising a roller having one face to cooperate with the engine member and another face to cooperate with the driving member, a stationary bracket, a second bracket pivoted thereto, and yielding means for holding the latter bracket in a
35 normal position, such roller being mounted for rotation in said second bracket.

40 9. In an engine starter drive, the combination, with a member of the engine to be started, of a rotatable shaft, a driving member mounted thereon for longitudinal movement thereof and rotary movement there-
45 with and composed of two parts, one a driving member proper adapted to engage the engine member and the other a control member operatively connected with the shaft and adapted to move the driving member proper along the shaft into engagement with the engine member, and means for moving such control member backwardly in event of backward rotation of the engine member, said means comprising a rotatable member
50 cooperating with the control member and with the engine member.

55 10. In an engine starter drive, the combination, with a member of the engine to be started, of a rotatable shaft, a driving member mounted thereon for longitudinal movement thereof and rotary movement there-
60 with and composed of two parts, one a driving member proper adapted to engage the engine member and the other a control member operatively connected with the shaft and adapted to move the driving member proper along the shaft into engagement with the
65 engine member, and means for moving such control member backwardly in event of backward rotation of the engine member.

70 11. In an engine starter drive, the combination, with a member of the engine to be started, of a rotatable shaft, a driving member mounted thereon for longitudinal movement thereof and rotary movement there-
75 with and composed of two parts, one a driving member proper adapted to engage the engine member and the other a control member operatively connected with the shaft and adapted to move the driving member proper along the shaft into engagement with the engine member, and means for moving such control member backwardly in event of backward rotation of the engine member, said means comprising a rotatable member
80 cooperating with the control member and with the engine member.

85 12. In an engine starter drive, the combination, with a member of the engine to be started, of a rotatable shaft, a driving member mounted thereon for longitudinal movement thereof and rotary movement there-
90 with and composed of two parts, one a driving member proper adapted to engage the engine member and the other a control member operatively connected with the shaft and adapted to move the driving member proper along the shaft into engagement with the engine member, and means for moving such control member backwardly in event of backward rotation of the engine member, said means comprising a rotatable member inter-
95 posed between the control member and engine member and having surfaces adapted to control and cooperate with both of the two last named members.

100 13. In an engine starter drive, the combination, with a member of the engine to be started, of a rotatable shaft, a driving member mounted thereon for longitudinal movement thereof and rotary movement there-
105 with and composed of two parts, one a driving member proper adapted to engage the engine member and the other a control member operatively connected with the shaft and adapted to move the driving member proper along the shaft into engagement with the engine member, and means for moving such control member backwardly in event of backward rotation of the engine member, said means comprising a roller mounted to rotate on an axis at right angles to said shaft and having a limited movement longitudinal of such axes, said roller being normally in the path of longitudinal movement of the control member and adapted to contact and be rotated by the engine member in its backward rotation and thereby to rotate the control member.

110 14. In an engine starter drive, the combination, with a member of the engine to be started, of a rotatable shaft, a driving member mounted thereon for longitudinal movement thereof and rotary movement there-
115 with and composed of two parts, one a driving member proper adapted to engage the engine member and the other a control member operatively connected with the shaft and adapted to move the driving member proper along the shaft into engagement with the engine member, and means for moving such control member backwardly in event of backward rotation of the engine member, said means comprising a roller mounted to rotate on an axis at right angles to said shaft and having a limited movement longitudinal of such axes, said roller being normally in the path of longitudinal movement of the control member and adapted to contact and be rotated by the engine member in its backward rotation and thereby to rotate the control member.

120 15. In an engine starter drive, the combination, with a member of the engine to be started, of a rotatable shaft, a driving member mounted thereon for longitudinal movement thereof and rotary movement there-
125 with and composed of two parts, one a driving member proper adapted to engage the engine member and the other a control member operatively connected with the shaft and adapted to move the driving member proper along the shaft into engagement with the engine member, and means for moving such control member backwardly in event of backward rotation of the engine member, said means comprising a roller mounted to rotate on an axis at right angles to said shaft and having a limited movement longitudinal of such axes, said roller being normally in the path of longitudinal movement of the control member and adapted to contact and be rotated by the engine member in its backward rotation and thereby to rotate the control member.

engine member, and means for moving such control member backwardly in event of backward rotation of the engine member, said means comprising a roller mounted to 5 rotate on an axis at right angles to said shaft and having a limited movement longitudinal of such axis, said roller having a periphery adapted to contact the engine member, and said control member and roller having co- 10 operating cone surfaces.

14. In an engine starter drive, the combination, with a member of the engine to be started, of a rotatable shaft, a driving member mounted thereon for longitudinal movement thereof and rotary movement therewith and composed of two parts, one a driving member proper adapted to engage the engine member and the other a control member operatively connected with the shaft and 15 adapted to move the driving member proper along the shaft into engagement with the engine member, and means for moving such control member backwardly in event of backward rotation of the engine member, said 20 means comprising a roller interposed between the engine member and control member, and a pivoted bracket in which the roller is mounted for rotation and for movement longitudinal of its axis, said roller having 25 surfaces cooperating with the engine member and control member.

15. In an engine starter drive, the combination, with a member of the engine to be started, of a rotatable shaft, a driving member mounted thereon for longitudinal movement thereof and rotary movement therewith and composed of two parts, one a driving member proper adapted to engage the engine member and the other a control 30 member operatively connected with the shaft and adapted to move the driving member proper along the shaft into engagement with the engine member, and means for moving such control member backwardly in 35 event of backward rotation of the engine member, said means comprising a roller interposed between the engine member and control member and a pivoted bracket in which the roller is mounted for rotation and for movement longitudinal of its axis, said roller having 40 surfaces cooperating with the engine member and control member said roller being normally spring pressed towards and in contact with the control 45 member.

16. In an engine starter drive, the combination, with a member of the engine to be started, of a rotatable shaft, a driving member mounted thereon for longitudinal movement thereof and rotary movement therewith and composed of two parts, one a driving member proper adapted to engage the engine member and the other a control member operatively connected with the shaft and 50 adapted to move the driving member proper 55

along the shaft into engagement with the engine member, and means for moving such control member backwardly in event of backward rotation of the engine member, said means comprising a roller mounted to 70 rotate on an axis at right angles to said shaft and having a limited movement longitudinal of such axis, said roller having a periphery adapted to contact the engine member, and said control member and roller having 75 cooperating cone surfaces and a spring for returning the driving member proper to normal position.

17. An engine starter drive including a rotatable shaft having a plain portion and a screw threaded portion, a driving member loosely mounted on said shaft for movement longitudinally on both said portions, a screw member threaded on the threaded portion and adapted to be automatically moved longitudinally by the rotation of said shaft and to contact the driving member and operatively connect it with the shaft for rotary movement therewith, an engine member with which the driving member is adapted to engage when moved longitudinally, and means controlled by the engine member in its backward rotation and acting upon the screw member to rotate the latter when the engine member is so rotated backwardly. 90

18. An engine starter drive including a rotatable shaft having a plain portion and a screw threaded portion, a driving member loosely mounted on said shaft for movement longitudinally on both said portions, a screw member threaded on the threaded portion and adapted to be automatically moved longitudinally by the rotation of said shaft and to contact the driving member and operatively connect it with the shaft for rotary movement therewith, an engine member with which the driving member is adapted to engage when moved longitudinally, and means controlled by the engine member in its backward rotation and acting upon the screw member to rotate the latter when the engine member is so rotated backwardly, said means comprising a roller interposed between the engine member and the screw member and having surfaces adapted to 100 contact with both of said last named members. 110

19. An engine starter drive including a rotatable shaft having a plain portion and a screw threaded portion, a driving member loosely mounted on said shaft for movement longitudinally on both said portions, a screw member threaded on the threaded portion and adapted to be automatically moved longitudinally by the rotation of said shaft and to contact the driving member and operatively connect it with the shaft for rotary movement therewith, an engine member with which the driving member is adapted to engage when moved longitudi- 120 125 130

dinally and means controlled by the engine member in its backward rotation and acting upon the screw member to rotate the latter when the engine member is so rotated backwardly, said means comprising a roller interposed between the engine member and the screw member and having a periphery adapted to contact the face of the engine member and having at one end a conical friction surface, said screw member having 10 a truncated conical friction surface adapted to cooperate with the cone surface of the roller.

VINCENT BENDIX.
